UNITED STATES PATENT OFFICE.

CHARLES W. HAMEL, OF ST. LOUIS, MISSOURI.

APPARATUS FOR POSITIONING ELASTIC TUBULAR COVERINGS ON THE HANDLES OF PLAYING CLUBS.

Application filed September 13, 1926. Serial No. 135,162.

This invention relates to novel method of and apparatus for positioning elastic tubular coverings such as rubber sleeve grips on golf clubs and parts thereof and the handles of other playing clubs.

Golf clubs are generally provided with leather grips, these grips are smooth and become slippery due to the perspiration of the hands and require the player to hold the club tightly in his hands. To eliminate these objectionable features a rubber sleeve or grip has come into use, such grip being slipped over the leather covering and held in position thereon by its own resiliency. A rubber grip enables the player to more securely hold the club without unduly straining the hands of the player, is not affected by moisture and the outer surfaces thereof can be roughened and given any desired shape so as to enable the player to obtain a more firm hold on the grip. However, no satisfactory method and means have been heretofore provided to place the rubber sleeve or grip on the golf clubs or the handles of other playing clubs in an efficient manner and without danger of impairing the resiliency of such elastic sleeves.

It is the object of this invention to provide simple and inexpensive means for placing an elastic tubular covering such as a rubber sleeve on the handle of a playing club whereby said sleeve will be firmly held in position and will not turn or slip when in use.

Other objects of the invention are to provide simple means for expanding the rubber sleeve in order to permit the insertion of the handle of the playing club therethrough and then removing said means so as to allow said rubber sleeve to be retained in proper position on said club in an expanded condition so that it will be secured against accidental displacement by its own resiliency.

With these and other objects in view, my invention consists in certain novel features of construction and arrangement of parts, hereinafter more fully described and claimed, and illustrated in the accompanying drawings, in which—

Figure 1 is a longitudinal cross section through my apparatus showing the grip of

a golf club in dotted lines in readiness to be inserted into the rubber sleeve.

Figure 2 is a similar view but showing the grip in full lines in position with the rubber sleeve partially released.

Figure 3 is an end elevational view of my apparatus.

Figure 4 is a perspective detail view of a cone-shaped member utilized to expand the rubber sleeve.

Figure 5 is a view similar to Figure 2 but showing the apparatus used in connection with a rubber sleeve to be used to cover and protect the inner end of the grip.

Figure 6 is an end elevational view of a modified form of my apparatus.

Figure 7 is a horizontal cross section taken on lines 7—7 of Figure 6.

Figure 8 is a vertical cross section taken through a detachable support used in conjunction with my apparatus.

Figure 9 is a front elevational view of same.

Figure 10 is a section taken vertically on line 10—10 of Figure 8.

Figure 11 is an end elevational view of a modified form of my apparatus.

Referring by numerals to the accompanying drawings, 10 indicates a ring provided with a central opening 11 of sufficient size to allow passage therethrough of the grip 12 of a golf club 13 and provided in its edge with radially disposed equi-distant notches 14. These notches receive rods 15 provided at one of their ends with suitable handles 16 and having their opposite ends adapted to receive a rubber sleeve 17 which it is desired to place on the grip of the golf club. These rods are of sufficient length to receive sleeve or elastic covering 17 and allow sufficient clearance between the ring 10 and said sleeve for receiving grip 12 and a plunger 18 which is a truncated cone member provided on its periphery with series of longitudinally disposed grooves 19 which are adapted to be traversed by rods 15. This member 18 is placed between rods 15 with the latter occupying grooves 19 and with the small end of said truncated cone member pointing towards sleeve 17. Golf club 13 is then inserted through opening 11 between

the rods 15 and the plunger 18 and the latter is then caused to move into the grip 12 of the golf club 13 so as to expand the rubber sleeve 17 and hold it in position on the grip 12.

rods 15 with the butt end of grip 12 bearing against the large end of member 18. Pressure is then applied to the golf club while ring 10 is held stationary thereby forcing member 18 forwardly into sleeve 17 and therethrough. During the passage of member 18 forwardly, sleeve 17 is expanded and is held in this expanded position by rods 15, one of their ends being held by ring 10 while the opposite ends bear against member 18. When member 18 is passed through sleeve 17, grip 12 will occupy the position shown in Figure 2 so that by withdrawing rods 15 sleeve 17 will contract and firmly engage said grip.

In the form shown in Figure 5, a short sleeve 20 is shown being positioned on the twine-covered portion 21 of grip 22. In the form shown in Figures 6 and 7, a modified form of apparatus is illustrated for positioning the rubber sleeve on the golf club, said form comprising box-shaped support 24 open at both ends and provided in its walls with apertures 25 through which pass screws 26 on the outer ends of which are threaded wing nuts 27 which bear against the outer faces of support 24. The inner ends of screws 26 have fixed thereto U-shaped brackets 28 which are presented towards the axis of the apparatus. Detachably inserted in the ends 29 of brackets 28 are rods 30 which occupy position parallel with the axis of the apparatus and equi-distant therefrom.

In using the device a rubber sleeve 31 is disposed within support 24 between the ends 29 of brackets 28 and screws 26 are moved inwardly to allow rods 30 to pass through said sleeve while being positioned in the apertured ends 29. Wing nuts 27 are now operated so as to bring screws 26 outwardly thereby bringing rods 30 away from the axis of the device and expanding sleeve 31 sufficiently to allow the insertion of the golf club therethrough as illustrated in Figures 6 and 7. When the golf club is properly positioned with respect to the rubber sleeve, rods 30 are withdrawn from their positions thereby releasing said sleeve so that the latter will engage the golf club.

In Figures 8 and 9 is illustrated the preferred form of a support for ring 10. This comprises a casting 34 having an adjustable screw 35 by means of which it can be detachably secured to a table or work bench 36 as shown. Extending upwardly from support 34 is a segmental portion 37 provided with a semi-circular flanged seat 38 adapted to receive the lower portion of ring 10. A complementary segmental member 39 provided with a flanged seat 40 is hinged at 41 to member 37 and is adapted to engage the upper half of the ring and lock the latter in position.

The free end of member 39 is adapted to

be secured in closed position by any suitable means such as a screw 42 which is pivotally mounted at 44 to member 37 and is adapted to be moved upwardly through a slot 45 formed in said free end. A wing nut 46 is threaded on screw 42 and is adapted to be screwed down and clamp the member 39 in closed position. Members 37 and 39 in addition to forming a support for ring 10 also serve to retain rods 15 in notches 14 so that said rods 15 can not become displaced from ring 10.

A rod 47 is slidably seated in member 34 a suitable distance below semi-circular seat 38 and is provided at its rear end with a hopper 48 which is preferably U-shaped in cross section and is adapted to receive plunger 18 when the latter is released by rods 15. The hopper 48 has an upwardly presented portion 48a which intersects the axis of the sleeve and forms an adjustable stop for plunger 18 so as to prevent movement of grip 12 beyond its proper position with respect to sleeve 17. Rod 47 is held in adjusted position by a screw 49 screw-seated in member 34 and having one end engaging said rod 47.

In the form shown in Figure 11 a ring 10a is formed integral with a support 15 and the latter is detachably secured to table or bench 51, by suitable attaching means 52.

The grooves 19 in plunger 18 are comparatively shallow being used merely as a guide for plunger 18 and the rods 15 extend a suitable distance beyond the periphery of said plunger so that the sleeve 17 is held in engagement with said rods which are stationary and the plunger is free to move longitudinally through said sleeve the movement of the plunger causing lateral expansion of said sleeve 17.

The diameters of rods 15 with respect to grooves 19 is such that rods 15 extend beyond the periphery of plunger 18 in order to reduce the frictional contact between tubular member 17 and said plunger and facilitate the passage of the latter therethrough.

My apparatus enables the use of tubular resilient members of comparative small diameters relative to the handle of the playing club, whereby when said tubular member is released on said club it is held thereon securely and all danger of slippage is eliminated.

By using my apparatus, the tubular members can be quickly positioned on the golf club in an efficient manner and the apparatus is so arranged that it can be readily set up for use in a store, shop and other places and taken down when not in use. No other tools are needed to operate my device and the latter does not require experienced operators, but can be used by any person.

While I have shown and described my invention as applied to golf clubs, it is to be

understood that my invention can be used for positioning elastic coverings on the handles of various playing clubs and other implements without departing from the spirit 5 of my invention.

I claim:

1. An apparatus of the class described comprising a stationary support provided with a central opening, a series of rods carried by said support and arranged in spaced relation with each other and with said opening, said rods being adapted to be removably inserted in an elastic tubular covering, and means insertable through said opening 15 in said support for moving said rods laterally, thereby expanding said tubular covering and allowing the insertion of the handle of a playing club through said support into said tubular covering.
2. An apparatus of the class described comprising a stationary support provided with a central opening, a series of rods removably carried by said support and arranged in spaced circumferential relation 25 about said opening, said rods being adapted to have positioned thereon an elastic tubular member, and a releasable member insertable through said opening between said rods for moving the same laterally to expand said 30 tubular member and allow the positioning thereinto of the handle of a club.
3. An apparatus of the class described comprising a stationary support provided with a central opening, a series of rods seated in said support and spaced equidistant about the axis of said opening, said rods being adapted to pass through a resilient tubular member, and means for moving said rods laterally to expand said tubular member and permit a portion of a golf club 40 to be inserted thereinto, said rods being removable from said tubular member to allow the latter to engage said golf club.
4. An apparatus of the class described comprising a stationary support having a central axially disposed opening, a series of rods removably seated in said support and in spaced concentric relation with the axis of said support, said rods being adapted to 45 pass through a resilient tubular member, and releasable means for moving said rods laterally to increase the diameter of said tubular member so as to permit positioning of a portion of a playing club through said

central opening in said support into said 55 tubular member, said rods being removable to release said tubular member and allow it to engage under tension said club.

5. An apparatus of the class described comprising a stationary support provided 60 with a central opening, a series of rods removably seated in said support and arranged in spaced concentric relation with the axis of said opening, said rods being adapted to pass through a resilient tubular member, releasable means for moving said rods laterally to increase the diameter of said 65 tubular member so as to permit positioning of a portion of a playing club through the opening in said support into said tubular member, said rods being removable to release said tubular member and allow it to engage under tension said club, and means for securing said support in a 70 stationary position.

6. An apparatus of the class described comprising a stationary support provided with a central opening, a series of rods adapted to be inserted in a resilient tubular member, means on said support for holding 80 said rods in spaced relation with each other and with the axis of said central opening, and releasable means for moving said rods laterally to expand said tubular member so as to permit positioning of a golf club with- 85 in said tubular member, said rods being removable so as to release said tubular member in position on said golf club.

7. An apparatus of the class described comprising a stationary support provided 90 with a central opening, a series of rods having one of their ends removably seated in said support in spaced relation with each other and with the axis of said central opening, said rods extending longitudinally 95 from said support and being adapted to have positioned thereon an elastic tubular member, and means insertable between said rods and through said tubular member so as to move said rods centrifugally to expand 100 said tubular member and allow the insertion therethrough of a portion of a playing club, said rods being removable so as to release said tubular member and allow it to resiliently engage said club.

In testimony whereof I hereunto affix my signature this 28 day of August, 1926.

CHARLES W. HAMEL.
